UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A HARP FOR HANGING LAMPS.

SPECIFICATION forming part of Design No. 17,881, dated November 15, 1887.

Application filed October 17, 1887. Serial No. 232,647. Term of patent 7 years.

To all whom it may concern:

Be it known that I, ALBERT PATITZ, of Meriden, in the county of New Haven and State of Connecticut, have invented a new Design for a Harp for Hanging Lamps; and I do hereby declare the following, when taken in connection with accompanying drawing and the letters of reference marked thereon, to be a full, clear, and exact description of the same, and which said drawing constitutes part of this specification, and represents a face view.

This invention relates to a design for that part of a hanging lamp by which the fount is supported and from which connections are made to the chains, the design relating specially to the arms or sides of the harp, which extend from the fount-holder upward; and it consists in the configuration and ornamentation of the arms, as shown in the accompanying illustration.

The arms at each side the fount-holder terminate at the bottom in a scroll shape, curving upward, with a branch therefrom curving downward and returned onto the body of the arm. The upper end of the arm is represented

as curved inward and downward, forming a scroll, with the representation of a branch continued down to the scroll at the lower end, and with the representation of a grape-leaf springing therefrom into the space between the body of the arm and the inner branch, the scroll-work representing a vine with the runners twining about the body of the vine, as shown in the accompanying illustration.

I claim—

The herein-described design for harp for hanging lamps, consisting in the representation of a vine, the body terminating at the lower end in an upwardly-turned scroll with a branch turned downward, the upper end represented as terminating in an inwardly and downwardly turned scroll with a branch extending to the lower scroll, and the representation of a leaf springing from the upper scroll, as shown in the accompanying illustration.

ALBERT PATITZ.
